Arthur J. Engman,
INVENTOR.

BY *J. A. Bishop*
ATTORNEY

UNITED STATES PATENT OFFICE.

ARTHUR J. ENGMAN, OF CANTON, OHIO.

METAL DOOR.

Application filed May 24, 1922. Serial No. 563,227.

92 To all whom it may concern:

Be it known that I, ARTHUR J. ENGMAN, a citizen of the United States, residing at Canton, in the county of Stark and State of Ohio, have invented a new and useful 55
02 Metal Door, of which the following is a specification.

This invention relates to metal doors and has for its object the provision of an improved means of securing the backing sheet or shell which holds the silencer in position, at the same time allowing a simple yet rigid construction for locking the panel moulding in place.

Another object is to greatly simplify the construction of this class of articles, thereby effecting a marked saving in the cost of labor for assembling and material.

In the drawings, in which corresponding numerals indicate similar parts;

9 Fig. 1 is a fragmentary view of a portion of a door showing a corner of a panel with the panel moulding and portions of the top rail and one of the side stiles.

Fig. 2 is a section on the line 2—2 of Fig. 1 looking in the direction indicated by the arrow.

Fig. 3 is a fragmentary perspective of portions of the panel, panel moulding, stile, 30 binder moulding, shell and silencer, spaced apart.

At 1 is indicated a vertical side rail or stile of a door. The ends of the sheet forming the stile are bent as shown at 2, forming oppositely arranged, in-turned flanges 3. Adjacent each of the flanges, there is secured within the stile a binder moulding 4, the said moulding contacting for a distance with its respective inner side of the stile as 40 at 5 and being spot welded to the said stile at said place of contact. At a point toward the outer end of the stile each binder moulding is bent inwardly as at 6 and then bent again toward the said outer end of the stile, 45 thus forming a flange 7 which is spaced from the side of the stile and parallel therewith. The fiber sheeting, paper or other material forming the silencer 8, lies against the inner side of the stile and is held in position by the shell 9. As clearly seen in Fig. 50 2, the flanges 7 are spaced the exact distance from their respective sides of the stile to receive the silencers 8 and shell 9 and hold them firmly against the said stile.

At the end of the portion 5 opposite the flange 6, each of the binders is bent inwardly as at 10, forward as at 11, then outwardly and parallel with the portion 10, as at 12 and then again forwardly as at 13. The portions 13 are each parallel with their respective sides of the stile and are spaced slightly therefrom. The said portions also terminate at a point spaced slightly from the flanges 3 at the edges of the sheet forming the stile. It is thus seen by reference to Figs. 2 and 3 that an open ended channel is formed between each of the binders and its respective side of the stile, the said channel terminating in a groove 14 formed by the portions 10, 11 and 12.

The panel moulding 15 has the usual central groove 16 to receive the panel 17, the extremities 18 of the said moulding lying within the open ended channels above referred to and terminating in in-turned flanges 19 which slide into the grooves 14 and thus lock the moulding in place.

From the foregoing it will be obvious that the labor involved in assembling my door is reduced to minimum. The binders 4 are first spot welded to the stile at the places indicated at 5 and the silencers 8 and shell 9 slid into place. The ends of the panel moulding are then slid into position between their respective sides of the stile and the opposite ends of the binders. It is also obvious that the foregoing construction will apply with equal advantage to the assembling of the top, bottom and middle rails of the door.

Having now described my invention, what I claim is:

1. In a metal door, a binder secured at its central portion to the stile of said door, the edges of said binder being spaced from said stile, a panel moulding having its edge inserted in the space at one end of said binder and a silencer and shell therefor having their edges inserted in the space at the opposite edge of said binder and being secured in position by said binder.

2. In a metal door, a binder secured at its central portion to the stile or rail of said door, one edge of said binder being spaced from the face of said stile, a silencer and shell therefor having their edges inserted between the binder and stile, and a panel moulding, the opposite edge of said

binder securing one portion of the panel moulding.

3. In a metal door, a binder spot welded at its central portion to the stile of said door, an in-turned portion formed on said binder at one side of said spot welded portion, a flange formed on the extremity of

said in-turned portion, a silencer and a shell therefor, one edge of said silencer and shell lying between said flange and stile and being secured in position by said flange. 10

In testimony that I claim the above I have hereunto subscribed my name.

ARTHUR J. ENGMAN.
